UNITED STATES PATENT OFFICE

2,173,718

SUCTION NOZZLE

Osmund Holm-Hansen, Stratford, Conn., assignor
to General Electric Company, a corporation of
New York

Application October 12, 1937, Serial No. 168,609

2 Claims. (Cl. 15—155)

The present invention relates to suction nozzles of the type adapted to be connected to a source of suction through a tube which in addition serves to move the suction nozzle over the surface being cleaned.

The object of my invention is to provide an improved construction and arrangement in suction nozzles of this type, and for a consideration of what I believe to be novel and my invention, attention is directed to the following description and the claims appended thereto.

In the accompanying drawing, Fig. 1 is a front elevation, partly broken away, of a suction nozzle embodying my invention; Fig. 2 is an end view of the nozzle; Fig. 3 is a sectional view taken on line 3—3 of Fig. 1; Fig. 4 is a sectional view taken on line 4—4 of Fig. 1; Fig. 5 is an exploded view of the nozzle, the parts being in section; Fig. 6 is a perspective view of one of the supports which pivotally connects the suction nozzle and the tube connected to a separate source of suction; and Fig. 7 is a diagrammatic view illustrating the use of the suction nozzle.

Referring to the drawing, there is shown a suction nozzle 1 having lips 2 and 3 on which are mounted surface contacting shoes 4 and 5. The end walls 6 of the suction nozzle terminate above the plane of the shoes 4 and 5 providing an opening 7 (Fig. 1) through which air flows across the surface being cleaned into the suction nozzle. The air flowing through the openings 7 is effective in removing surface litter. At the center of the nozzle is a horizontal wall 8 having upturned ends 9 providing opposed circular passages 10 facing lengthwise of the suction nozzle. The passages 10 serve as the discharge outlet of the suction nozzle. On the lower side of the wall 8 is a rib 11 which extends substantially to the plane of the shoes 4 and 5 and contacts surface being cleaned. The rib 11 is particularly effective in case one end of the suction nozzle projects beyond the edge of a rug while the other end is on the rug. In this condition, the projecting end of the suction nozzle is spaced a considerable distance above the floor, and accordingly, there is very little suction in the portion of the nozzle between the rib 11 and the projecting end of the nozzle and there is a relatively large air flow through this part of the nozzle. Due to the rib 11, the suction is not decreased throughout the full length of the suction nozzle. The large air flow through the projecting part of the nozzle results in a relatively high resistance which limits the flow through this part of the nozzle. This results

in a pressure differential between the discharge outlet and the portion of the nozzle on the rug between the rib 11 and the end of the nozzle which is effective in creating a suction over this part of the nozzle. It is therefore apparent that the cleaning effect of the nozzle is not as greatly decreased by accidental movement of an end of the nozzle off the edge of the rug. To obtain greater advantage of this construction the top walls of the suction nozzle are proportioned to provide for a smooth flow of air from the nozzle lips to the discharge outlet under normal conditions when the full length of the nozzle rests on the surface being cleaned. That is, the section of the nozzle decreased toward the ends of the nozzle. With this design, there is obviously a greater restriction of air flow through the end of the nozzle which projects beyond the edge of the rug.

Connected to the openings 10 of the suction nozzle is a tube 12 having forked ends 13 registering with the openings 10. Gaskets 14 are arranged between the openings 10 and the ends 13. The tube 12 is pivotally connected to the suction nozzle by supports having ends 15 pivotally engaging the ends 13 and having portions 16 fitting over the outside walls of the suction nozzle and secured thereto, for example, by screws 17. These supports provide a convenient arrangement for connecting the tube to the suction nozzle. The portions 15 may be fitted over the ends 13 and the gaskets 14 assembled in place. The assembly may then be inserted in place in the suction nozzle and secured therein by the screws 17.

In the use of the suction nozzle, a rigid tube 18 is fitted within the tube 12 and connected by means of a flexible hose 19 to a source of suction. The tube 18 serves as a handle by means of which the suction nozzle is moved over the surface being cleaned. The pivotal connection to the suction nozzle permits the handle to be lowered close to the floor when cleaning under furniture. As shown in Fig. 3, the rear portion of the suction nozzle above the wall 8 is cut away to permit the tube 12 to be moved to a substantially horizontal position.

What I claim as new and desire to secure by Letters Patent of the United States is:

1. In a vacuum cleaner, a suction nozzle having top walls and side walls terminating in surface contacting lips, a longitudinally extending wall below the top walls and above the nozzle lips, portions on said longitudinally extending wall and said top walls cooperating to provide a

pair of discharge outlets below said top walls and facing opposite ends of the suction nozzle, a wall on the lower side of said longitudinally extending wall extending substantially to the plane of the nozzle lips and dividing the interior of the nozzle into a pair of passages spaced apart lengthwise of the nozzle and leading from the nozzle lips to said discharge outlets, and a tube having a pair of openings respectively connected to said outlets for connecting the passages to a source of suction and for moving the nozzle over the surface being cleaned.

2. In a vacuum cleaner, a suction nozzle hav-

ing downwardly disposed lips, walls of said nozzle defining a recess in the top thereof above the nozzle lips with opposed discharge outlets in the end walls of the recess facing opposite ends of the nozzle, a suction tube having forked ends fitting in and spaced from the bottom wall of said recess, the ends thereof facing said discharge outlets, and a support having a portion extending in said recess and pivotally supporting one of said forked ends and having a portion extending over and fixed on the adjacent part of the suction nozzle.

OSMUND HOLM-HANSEN.
